United States Patent Office

Des. 194,758
Patented Mar. 5, 1963

194,758

PANTAGRAPH OR SIMILAR ARTICLE

Pasquale A. Mercorelli, 441 Summer Ave., Newark, N.J.

Filed May 24, 1961, Ser. No. 65,315

Term of patent 14 years

(Cl. D52—6)

*Fig: 7**Fig: 8**Fig: 9*FIGURE 1 is a perspective view of a pantagraph or similar article showing my new design;

FIGURE 2 is a front elevational view of the base thereof;

FIGURE 3 is a left side elevational view of the base thereof;

FIGURE 4 is a rear elevational view of the base thereof;

FIGURE 5 is a right side elevational view of the base thereof;

FIGURE 6 is a top plan view of the base thereof;

FIGURE 7 is a vertical sectional view taken on the line 7-7 in FIGURE 6;

FIGURE 8 is a top plan view showing the base with the arms attached;

FIGURE 9 is a complete elevation from the left side of FIGURE 3.

I claim:

The ornamental design for a pantagraph or similar article, as shown.
